UNITED STATES PATENT OFFICE.

ROBERT W. KING, OF NEW YORK, N. Y., ASSIGNOR TO WESTERN ELECTRIC COMPANY,
INCORPORATED, OF NEW YORK, N. Y., A CORPORATION OF NEW YORK.

THERMIONIC DEVICE AND METHOD OF EVACUATING THE SAME.

Application filed September 24, 1920. Serial No. 412,587.

This invention relates to the production of electron discharge devices, and pertains more especially to the evacuation of the containing vessels of such devices.

5 The object of this invention is to obtain quickly and expeditiously a high degree of vacuum within the containing vessels of electron discharge devices.

This object is attained by removing the 10 occluded gases from the electrodes by electron bombardment and then cleaning up the gases within the vessel by vaporizing calcium within the vessel to absorb the gases. The calcium is preferably supported by one of 15 the electrodes and is heated to its vaporization temperature by electron bombardment.

In the accompanying drawings Fig. 1 shows a two electrode tube embodying one 20 form of anode pocket, Fig. 2 shows a three electrode tube embodying a different form of anode pocket, and Fig. 3 shows part of an anode similar to that of Fig. 1 except that a third form of anode pocket is shown in Fig. 3.

25 In Fig. 1 the tube 4 comprises envelope 5 of glass or the like having the usual inwardly projecting stem 6 from which rises arbor 7 of glass or the like. The arbor 7 carries a support 8 on which a cathode 9 is mounted. 30 The arbor also carries supports (not shown) on which anode plate 10 is mounted. Anode plate 10 carries conductors 11, which support anode plate 12. Leading in wires for the cathode are shown at 13 and 14. A leading in wire for the anode is shown at 15.

The cathode which in the form shown is filamentary, is preferably of the type having a coating of oxides of alkaline earth metals, since that type has special advantages in connection with this invention as will be pointed out in detail hereinafter. An example of such a cathode is disclosed in United States Patent to Nicolson and Hull No. 1,209,324, December 19, 1916, electron emitting cathode and the process of manufacturing the same.

45 On the anode plate 12 is a pocket 16 for holding a small piece of calcium 17. The side of the pocket is formed by metallic strip 18 in the form of a vertical trough, the edges 50 19 and 20 of the trough being welded to anode plate 12. The bottom of the pocket is formed by a metallic piece 21, which has a portion 22 welded to the anode plate 12 and has a portion 23 bent to form a right angle 55 with the portion 22 and cut to the proper

shape to close the bottom end of the trough.

In Fig. 2 the tube 24 comprises an envelope 25 or glass or the like having a stem 26. The stem carries a metallic collar 27 from which rise anode plates 28 and 29. At their tops 60 the anode plates carry a metallic box 30 containing a block of "lavite" 31 from which are supported a double surface grid 32 and a cathode filament (not shown), the filament being located between the two grid surfaces. 65 Leading in wires for the filament are shown at 33 and 34. A leading in wire for the anode is shown at 35 and one for the grid is shown at 36. The filament preferably has a coating such as that referred to in the description of Fig. 1.

On the anode plate 29 is a pocket 37 for holding a piece of calcium 17 like that referred to in the description of Fig. 1. The pocket 37 is formed by bowing a square 38 of 70 sheet metal into a shallow dish form and welding the corners of the square to the plate 29, with one of the upper edges of the dished square bowed away from the plate 29 sufficiently to permit inserting the calcium in the 75 pocket.

Fig. 3 shows an anode plate 39 which is like plate 12 of Fig. 1, except that the plate 39 has a pocket 40 formed on it by stamping the pocket from the plate 39, the pocket opening toward the cathode and having a suitable closure 41 placed over the opening. The closure 41 is a metallic square held in place by tongues 42 and 43, which being stamped from the pocket, affords communication between the pocket and the vessel. The closure 41 is slid between the tongues and the pocket and preferably the edges of the closure are welded to the plate 39 at the edges of the pocket.

In the preferred method of evacuating tubes such, for example, as those described, the tube is sealed on a suitable pumping apparatus, for instance, a rotary mechanical pump and a mercury aspirator, pumped for about 3 or 4 minutes, and then baked for about 15 minutes by means of an oven surrounding it to liberate vapor and gas from the tube walls and electrodes, the temperature of the oven being brought up to about 400° centigrade. The tube is then allowed to cool, the cooling requiring about a minute, after which the anode and the grid are bombarded, (a) separately for about a minute each; (b) electrically connected for about a 105 110

minute. This bombardment is not sufficiently vigorous to vaporize the calcium, but is designed to liberate gas from the plate and the grid. Following this bombardment, the 5 plate and the grid are electrically connected and the plate bombarded by electrons from the cathode vigorously enough to heat the plate so that the calcium will be vaporized. The pumping of the tube is preferably continued 10 during all of the foregoing steps. The pressure in the tube should be low enough before the vigorous bombardment of the anode is started, to insure that the plate can be heated to the vaporization temperature 15 of the calcium by the electron bombardment of the plate without undue injury to the cathode by bombardment due to positive gas ions. With the alkaline earth oxide coated filament referred to above, it 20 is only necessary that the pressure be as low as about .008 millimeters of mercury. The use of this type of filament presents a great advantage in this respect, for, in a poor vacuum the coated filament is much more 25 active than a tungsten filament, for example, and therefore, less time is required in the case of the coated filaments than in the case of the tungsten filament to pump the tube to the degree of vacuum necessary before 30 the bombardment for vaporizing the calcium can be begun. It requires about 3 or 4 minutes of the vigorous bombardment to heat the calcium hot enough to vaporize it. During this time there is haze in the 35 tube and the pressure in the tube increases. After the calcium is hot enough to be vaporized, only 5 or 6 seconds time is required to clean up the gases, the haze in the tube disappearing as the gases are absorbed. If the 40 bombardment is continued after this stage has been reached, calcium vapor will condense on the tube walls as a black deposit, but will not affect the operation of the tube materially as the vapor pressure of the calcium 45 as well as that of the compounds of calcium with the gases cleaned up is negligibly low.

Although it has been stated above that in the preferred method of evacuating tubes 50 the tubes are baked for about 15 minutes after pumping has progressed for 3 or 4 minutes, in some instances the evacuation has been satisfactorily carried out without baking, and in other instances of successful 55 evacuation the baking has been done before any preliminary pumping. In any case in which the tubes are baked, the duration of

the baking may vary considerably from the 15 minute period referred to above, depending upon the tube. 60

In general, the duration of the baking should be longer the greater the amount of energy the tube will be called upon to dissipate during normal operation.

If instead of using calcium vapor to clean 65 up the gases in the tube, pumping is resorted to, as formerly, for securing the final stage of evacuation, then instead of requiring but a few minutes of bombardment to finish the evacuation, about 20 minutes will 70 ordinarily be required. Thus, the use of the calcium effects a great saving in time.

While calcium is the preferred material 75 for use in the anode pocket, other vaporizable material, for example, magnesium, barium or strontium, having low vapor pressure and capable of combining with the gases to be removed from the tube to form compounds having negligibly low vapor pressure at the operating temperature, may 80 be used in the pocket without departing from the invention.

Although the preferred method of supporting the calcium adjacent the anode is by means of a pocket on the anode, the 85 invention may assume other aspects. For instance, the anode plates may be made of a nickel-calcium alloy containing a small percentage of calcium, or the plates may be coated with the calcium, without departing 90 from this invention.

The tubes shown in Figs. 1 and 2 embody details of construction which are no part of this invention, the tube of Fig. 1 being claimed in the patent to H. J. Van Der Bijl, 95 U. S. Patent No. 1,479,778, issued January 1, 1924, entitled Vacuum tube devices, assigned to the assignee of this application, and the tube of Fig. 2 being claimed in an application of William F. Hendry, Serial 100 No. 217,565, filed Feb. 16, 1918, entitled Electron discharge devices, assigned to the assignee of this application.

What is claimed is:

In a vacuum tube, a plate electrode, said 105 plate having a portion struck out to form a pocket, a cover for said pocket, tabs cut out from said plate to engage said cover to hold it in position, and vaporizable material contained within said pocket. 110

In witness whereof, I hereunto subscribe my name this 20th day of September, A. D. 1920.

ROBERT W. KING.
